RECLINING ARTICLE OF FURNITURE

Anton Lorenz, Buffalo, N. Y.

Application August 22, 1946, Serial No. 692,225
In Czechoslovakia March 15, 1946

7 Claims. (Cl. 155—105)

1

This is a continuation-in-part of patent application Ser. #635,623, relating to "An adjustable reclining chair or the like," filed December 18, 1945, and of patent application Ser. #637,936, relating to "A reclining article of furniture," filed December 29, 1945, and of patent application Ser. #640,694, relating to "A reclining article of furniture," filed January 12, 1946.

This invention relates to articles of furniture, and more particularly to a reclining article of furniture, wherein the seat and the back-rest form movable links of a polygonal compound linkage swingably mounted on a support, a portion of the latter forming the stationary link of said linkage.

An object of the present invention is to provide a reclining article of furniture of above described type, wherein the movable members of the article of furniture are very well balanced, so that an occupant resting in the article of furniture may bring the movable members of the article of furniture from one position into another position without great effort.

A further object of the present invention is to provide a reclining article of furniture of above described type equipped with a leg-rest swingably mounted on the seat and controlled by a controlling mechanism, wherein the leg-rest may be swung through a relatively large angle during a movement of the movable members of the article of furniture from their sitting position into their extreme reclined position, so that the leg-rest may be brought into a substantially horizontal position when the members of the article of furniture are in their extreme reclined position.

Still another object of the invention is to improve upon reclining articles of furniture as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of a reclining chair according to the invention.

Fig. 2 is a side elevational view of another embodiment of a reclining chair according to the invention.

Fig. 3 is a sectional view taken on line 3—3 of Fig. 2.

Fig. 4 is a side elevational view of a further embodiment of a reclining chair according to the invention, and

Fig. 5 is a side elevational view of still another embodiment of a reclining chair according to the invention.

Referring now to Fig. 1, 10 generally indicates

2

a support, the side frames of which are connected with each other by cross bars 12.

A back-rest 14 is pivotally connected at its lower end with the support 10 at 16. On each side of the chair, the rear portion of a top link 18 is pivoted to an intermediate point 20 of the back-rest 14 above the pivotal connection 16 of the latter with the support 10. The front portion of each top link 18 is pivotally connected at 22 with the upper end portion of a connecting link 24, the lower end portion of which is pivoted to the support 10 at 26. Thus, the movable back-rest 14, the movable top link 18, the movable connecting link 24 and the stationary portion of the support 10 between the pivotal connection 26 of the connecting link 24 with the support and the pivotal connection 16 of the back-rest 14 with said support form the links of a four-bar link-mechanism.

20 The rear portion of a seat 28 is pivoted to the support 10 at 30 at a point spaced from the pivotal connection 16 between the back-rest 14 and the support 10. On each side of the chair, the lower end portion of a front link 32 is pivoted to the front portion of the seat 28 at 34. The upper end portion of said front link 32 is pivoted to the top link 18 at 22 in coaxial alignment with the pivotal connection between said top link 18 and the connecting link 24.

25 The thus connected four-bar link-mechanism 14, 18, 24, 26—16 and the link chain 28, 32 form a polygonal compound linkage. The links of said polygonal compound linkage may be readily arranged in such a manner and in such proportions, that the movable members of the chair are very well balanced, so that an occupant resting in the chair may bring the movable members of the chair from one position (for example the sitting position shown in full lines) into another position (for example the extreme reclined position shown in dash and dot lines) without great effort. The sitting position is limited by a stop 36 mounted on the support 10, against which the seat 28 comes to a rest. The extreme reclined position is limited by a stop 38 mounted on the support 10, against which the connecting link 24 comes to a rest when the latter is in the extreme reclined position.

30 The upper end of a leg-rest 40 is pivoted to the front portion of the seat 28 at 42. One end of a controlling link 44 is pivoted to the leg-rest 40 at 46, the other end of said controlling link 44 is pivotally connected with an upward extension of the support 10 by means of a pivot 48. Said controlling link 44 serves to control the swinging movements of the leg-rest 40 about its pivot 42 when the movable members of the chair are brought from one position into another one. If, for example, the occupant resting in 35 the chair leans the weight of his body against

the back-rest 14 and brings the movable members into the extreme reclined position shown in dash and dot lines, the leg-rest controlled by the controlling link 44 is brought into a substantially horizontal position.

The upward extension of the support 10 is provided with a series of bores 50, and the pivot 48 may be inserted into one of said bores for changing the degree of movement of the leg-rest 40 by the controlling link 44, if so desired.

Although Fig. 1 does not illustrate a locking device for holding the movable members of the chair in any desired position, it is understood that any suitable locking device may be associated with at least one member of the link-system of the chair.

Furthermore, it is understood, that one or more of the links of the chair may be made of adjustable length so as to vary the degree of movements of the links when the movable members of the chair are brought from one position into another one.

Moreover, one or more links of the chair may be of bent shape instead of the straight shape shown in Fig. 1.

The polygonal compound linkage of the chair shown in Fig. 2 is the same as that of the chair shown in Fig. 1. Again, the lower end of the back-rest 114 is pivoted to the support 110 at 116. The rear end of the top link 118 is pivoted to an intermediate point of the back-rest 114 at 120. The front portion of said top link 118 is pivotally connected with the upper end of the connecting link 124 at 122, and the lower end of said connecting link 124 is pivoted to the support 110 at 126. The rear portion of the seat 128 is pivotally connected with the support 110 at 130 at a point spaced from the pivotal connection 116 between the back-rest 114 and the support 110. The front portion of said seat 128 is pivotally connected with the lower end of the front link 132 at 134. The upper end of said front link 132 is pivoted to the top link 118 at the point 122 coaxially arranged with the pivotal connection between the top link 118 and the connecting link 124.

The leg-rest 140 pivotally connected with the seat 128 at the point 134 coaxially arranged with the pivotal connection between the seat 128 and the front link 132 is equipped with an upward extension 152. Furthermore, the top link 118 has an extension 154 projecting beyond its pivotal connection 122 with the connecting link 124. A helical spring 156 having its ends connected with the seat 128 and the leg-rest 140 tends to urge the extension 152 of the leg-rest 140 against a lug 158 arranged on the extension 154 of the top link 118. When the movable members of the chair are brought from one position into another one, for example from the sitting position shown in full lines into the extreme position shown in dash and dot lines, the lug 158 loosely connected with the extension 152 controls the movements of the leg-rest 140.

The sitting position of the movable members of the chair is limited by a stop 136 mounted on the support 110 for cooperation with the seat 128; the extreme reclined position of the movable members of the chair is limited by a stop 160 arranged on the support 110 for cooperation with the back-rest 114.

The movable members of the chair may be held in any desired position, for example in the extreme reclined position shown in dash and dot lines, or in any other intermediate reclined posi-

tion by means of a locking device generally indicated by 162 and arranged on the pivot 120 connecting the top link 118 with the back-rest 114. As best shown in Figs. 2 and 3, said locking device 162 comprises a handle 164 screwed on the threaded end of the pivot 120. Said pivot 120 has a head 166 resting against the surface of the back-rest 114. A square portion 168 of the pivot 120 is inserted into a corresponding square aperture of the back-rest 114, whereby the pivot 120 is prevented from rotation. When the user of the chair loosens the locking handle 164, the surface hub 170 of said handle is disengaged from the surface of the top link 118, so that the movable members of the chair may be freely moved from one position into another one. When the locking handle 164 is tightened, the surface of the hub of the handle is pressed against the top link 118, whereby the latter is pressed against the back-rest 114 engaged with the head 166 of the pivot 120, so that the members of the chair are held in their position. Of course, any other type of locking device may be used instead of said locking device 162, if desired. Furthermore, it may be mentioned, that this type of locking device may also be used in the chair shown in Fig. 1.

When the movable members of the chair shown in Fig. 2 are held by the locking device 162 in any desired position, the extension 152 of the leg-rest 140 may be used as a handle for swinging the leg-rest 140 independently of the other members of the chair about its pivot 134 into a desired position relative to the seat 128, wherein the leg-rest 140 may be held by a holding device (not shown in Fig. 2).

According to the embodiment of an adjustable reclining chair shown in Fig. 4, the support 210 is in the shape of a casing.

The back-rest 214 is pivoted to the support 210 at 216. On each side of the chair the rear portion of the top link 218 is pivoted to an intermediate point of the back-rest 214 at 220. The upper end of a connecting link 224 is pivoted to the top link 218 at 222. The lower end of said connecting link 224 is pivoted to the support 210 at 226. Again, the movable back-rest 214, the movable top link 218, the movable connecting link 224, and the stationary portion of the support 210 between the pivots 216 and 226 form the links of a four-bar link-mechanism.

The top link 218 has an extension 254 projecting beyond its pivotal connection 222 with the connecting link 224. According to Fig. 4, the upper end portion of the front link 232 is pivoted to said extension 254 of the top link 218 at 272 at a point spaced from the pivotal connection 222 between the top link 218 and the connecting link 224. The lower end of the front link 232 is pivoted at 234 to the seat 228, the rear end of which is pivoted to the support 210 at the point 230 spaced from the pivotal connection 216 between the back-rest 214 and the support 210.

A leg-rest 240 swingably mounted on the front portion of the seat 228 at 242 has an upward extension 252 pivotally connected with one end of a controlling link 244 at 274. The other end of said controlling link 244 is pivoted at 276 to an arm 278 rigidly connected with the connecting link 224 so as to participate in the movements of the latter.

When the swingable back-rest 214 is brought from the upright position shown in full lines into the extreme reclined position shown in dash and dot lines, the seat 228 forming a member

of the polygonal compound linkage is swung about its pivot 230 from the sitting position shown in full lines into the reclined position shown in dash and dot lines and the leg-rest 240 is brought from the sitting position shown in full lines into the almost horizontal position shown in dash and dot lines through the medium of the arm 218 and the controlling link 244.

The sitting position of the movable members of the chair is limited by an abutment of the seat 228 on the upper surface of the support 210; the extreme reclined position is limited by a stop 260 arranged on the support 210 for cooperation with the back-rest 214.

The movable members of the chair may be held in any desired position by means of the locking device 262 arranged on the pivotal connection 220 between the back-rest 214 and the top link 218.

In the adjustable reclining chair shown in Fig. 5, the back-rest 314 is pivoted at 316 to a lug 380 of the support 310. On each side of the chair the rear portion of the top link 318 is pivoted to an intermediate point of the back-rest 314 at 320. The front portion of said top link 318 is pivoted at 322 to the upper end of a connecting link 324, the lower end of which is pivoted to the support 310 at 326. Thus the movable back-rest 314, the movable top link 318, the movable connecting link 324 and the stationary portion of the support 310 between the pivots 316 and 326 form the links of a four-bar link-mechanism. The rear portion of the seat 328 is pivoted to the lug 380 of the support 310 at 330 at a point spaced from the pivotal connection 316 between the back-rest 314 and the lug 380. The front portion of the seat 328 is pivoted at 334 to the lower end of a front link 332, the upper end of which is pivoted to an intermediate point of the top link 318 at the point 382 spaced from the pivotal connection 322 between the top link 318 and the connecting link 324.

The sitting position of the movable members of the chair shown in full lines is limited by a stop 336 mounted on the support 310 for cooperation with the seat 328; the extreme reclined position of the movable members of the chair shown in dash and dot lines is limited by a stop 338 mounted on the support 310 for cooperation with the connecting link 324.

The movable members of the chair may be held in any desired position by means of a locking device 326 arranged on the pivotal connection 320 between the back-rest 314 and the top link 318.

I have described preferred embodiments of my invention, but it is understood that this disclosure is for the purpose of illustration, and that various omissions or changes in shape, proportion, and arrangement of parts as well as the substitution for equivalent elements for those, herein shown and described, may be made without departing from the spirit and scope of the invention as set forth in the appended claims. Furthermore, the invention may be applied to other articles of furniture than the type of chairs shown in the drawings, for example to desk chairs, garden chairs, chairs for use in railroad cars, chairs for use in airplanes, lounges, etc.

What I claim is:

1. A reclining article of furniture, comprising: a support, a back-rest pivoted to said support, a top link, the rear portion of said top link being pivoted to an intermediate point of said back-rest above said pivotal connection between the back-rest and the support, a connecting link, one end

portion of said connecting link being pivoted to the front portion of said top link, the other end portion of said connecting link being pivoted to said support at a point spaced from the pivotal connection between the back-rest and the support, said back-rest, said top link, said connecting link and the stationary portion of the support between the pivotal connection of the connecting link with the support and of the back-rest with the support forming the links of a four-bar link-mechanism, a seat, the rear portion of said seat being pivoted to said support at a point spaced from the pivotal connection between the back-rest and the support, and a front link, one end portion of said front link being pivoted to the front portion of said seat, and the other end portion of said front link being pivoted to the top link.

2. A reclining article of furniture, comprising: a support, a back-rest pivoted to said support, a top link, the rear portion of said top link being pivoted to an intermediate point of said back-rest above said pivotal connection between the back-rest and the support, a connecting link, one end portion of said connecting link being pivoted to the front portion of said top link, the other end portion of said connecting link being pivoted to said support at a point spaced from the pivotal connection between the back-rest and the support, said back-rest, said top link, said connecting link and the stationary portion of the support between the pivotal connection of the connecting link with the support and of the back-rest with the support forming the links of a four-bar link-mechanism, a seat, the rear portion of said seat being pivoted to said support at a point spaced from the pivotal connection between the back-rest and the support, a front link, one end portion of said front link being pivoted to the front portion of said seat, the other end portion of said front link being pivoted to the top link, and locking means associated with at least one member of the link-system of the article for locking the movable members thereof in a predetermined position.

3. A reclining article of furniture, comprising: a support, a back-rest pivoted to said support, a top link, the rear portion of said top link being pivoted to an intermediate point of said back-rest above said pivotal connection between the back-rest and the support, a connecting link, one end portion of said connecting link being pivoted to the front portion of said top link, the other end portion of said connecting link being pivoted to said support at a point spaced from the pivotal connection between the back-rest and the support, said back-rest, said top link, said connecting link and the stationary portion of the support between the pivotal connections of the connecting link with the support and of the back-rest with the support forming the links of a four-bar link-mechanism, a seat, the rear portion of said seat being pivoted to said support at a point spaced from the pivotal connection between the back-rest and the support, and a front link, one end portion of said front link being pivoted to the front portion of said seat, and the other end portion of said front link being pivoted to the top link at a point coaxial with the pivotal connection between the top link and the connecting link.

4. A reclining article of furniture, comprising: a support, a back-rest pivoted to said support, a top link, the rear portion of said top link being pivoted to an intermediate point of said back-rest above said pivotal connection between the

back-rest and the support, a connecting link, one end portion of said connecting link being pivoted to the front portion of said top link, the other end portion of said connecting link being pivoted to said support at a point spaced from the pivotal connection between the back-rest and the support, said back-rest, said top link, said connecting link and the stationary portion of the support between the pivotal connections of the connecting link with the support and of the back-rest with the support forming the links of a four-bar link-mechanism, a seat, the rear portion of said seat being pivoted to said support at a point spaced from the pivotal connection between the back-rest and the support, and a front link, one end portion of said front link being pivoted to the front portion of said seat, and the other end portion of said front link being pivoted to a point of the top link spaced from the pivotal connection between the top link and the connecting link.

5. A reclining article of furniture, comprising: a support, a back-rest pivoted to said support, a top link, the rear portion of said top link being pivoted to an intermediate point of said back-rest above said pivotal connection between the back-rest and the support, a connecting link, one end portion of said connecting link being pivoted to the front portion of said top link, the other end portion of said connecting link being pivoted to said support at a point spaced from the pivotal connection between the back-rest and the support, said back-rest, said top link, said connecting link and the stationary portion of the support between the pivotal connections of the connecting link with the support and of the back-rest with the support forming the links of a four-bar link-mechanism, said top link having an extension projecting beyond its pivotal connection with the connecting link, a seat, the rear portion of said seat being pivoted to said support at a point spaced from the pivotal connection between the back-rest and the support, and a front link, one end portion of said front link being pivoted to the front portion of said seat, and the other end portion of said front link being pivoted to said extension of the top link.

6. A reclining article of furniture, comprising: a support, a back-rest pivoted to said support, a top link, the rear portion of said top link being pivoted to an intermediate point of said back-rest above said pivotal connection between the back-rest and the support, a connecting link, one end portion of said connecting link being pivoted to the front portion of said top link, the other end portion of said connecting link being pivoted to said support at a point spaced from the pivotal connection between the back-rest and the support, said back-rest, said top link, said

connecting link and the stationary portion of the support between the pivotal connections of the connecting link with the support and of the back-rest with the support forming the links of a four-bar link-mechanism, a seat, the rear portion of said seat being pivoted to said support at a point spaced from the pivotal connection between the back-rest and the support, and a front link, one end portion of said front link being pivoted to the front portion of said seat, and the other end portion of said front link being pivoted to an intermediate point of the top link between the pivotal connections of the latter with the connecting link and the back-rest.

15 7. A reclining article of furniture, comprising: a support, a back-rest pivoted to said support, a top link, the rear portion of said top link being pivoted to an intermediate point of said back-rest above said pivotal connection between the back-rest and the support, a connecting link, one end portion of said connecting link being pivoted to the front portion of said top link, the other end portion of said connecting link being pivoted to said support at a point spaced from the pivotal connection between the back-rest and the support, said back-rest, said top link, said connecting link and the stationary portion of the support between the pivotal connections of the connecting link with the support and of the back-rest with the support forming the links of a four-bar link-mechanism, a seat, the rear portion of said seat being pivoted to said support at a point spaced from the pivotal connection between the back-rest and the support, a front link, one end portion of said front link being pivoted to the front portion of said seat, the other end portion of said front link being pivoted to the top link, a leg-rest swingably mounted on the front portion of said seat, and a controlling means on a member of said article for controlling movements of the leg-rest, said member being exclusive of the seat.

ANTON LORENZ.
